UNITED STATES PATENT OFFICE.

FRANK T. WHEELER, OF PLAINVILLE, CONNECTICUT, ASSIGNOR TO THE TRUMBULL ELECTRIC MANUFACTURING CO., OF PLAINVILLE, CONNECTICUT, A CORPORATION OF CONNECTICUT.

ELECTRIC SWITCH

Application filed July 9, 1919. Serial No. 309,643.

To all whom it may concern:

Be it known that I, FRANK T. WHEELER, a citizen of the United States of America, residing at Plainville, Connecticut, have invented a new and useful Electric Switch, of which the following is a specification.

This invention relates particularly to inclosed switches of the so-called "safety" type wherein the box in which the switch is mounted can only be opened when the switch is thrown to the "off" circuit position. In these switches, as heretofore constructed, the opening of the switch box exposes certain live parts of the switch. It is the object of my present invention to guard these live parts of the switch when the box is open and to protect the operator from contact with such parts.

The invention accordingly resides in the provision of a guard which covers the live parts of the switch mechanism, but leaves other parts, such as the fuses, uncovered and accessible. This guard may be secured in position by means of screws or by means of a hinge and a suitable seal may be provided.

In the accompanying drawing, I have illustrated the invention embodied in different practical forms, but wish it understood that further modifications may be made without departure from the true spirit and scope of the invention.

Fig. 1, is a front view of an inclosed switch with the box shown open and the guard in its protective position.

Fig. 2 is a longitudinal sectional view of the same.

Fig. 3 is a broken detail view of a portion of the guard and supporting bracket.

Fig. 4 is a view of a slightly modified form of the invention.

5 designates the box body provided with the usual hinged cover 6. The switch mechanism may of course be of any suitable construction and is shown generally as consisting of switch blades 7 adapted for engagement with contacts 8, said switch blades being hinged at 9 and operated by an external handle 10.

The switch shown is provided with fuses 11 engaged in suitable clips 12, and both the switch and the fuses are shown mounted on the same base 13.

The switch shown in the drawings is of the "bottom fused" type with the switch mechanism occupying the upper portion of

the box and the fuses disposed in the lower portion of the box.

The guard consists of a plate 14 usually of sheet metal, secured in the portion of the box containing the switch mechanism and terminating at the end of such switch mechanism so as to leave the fuses wholly exposed and easily accessible.

This guard plate is preferably disposed substantially flush with the rim of the box and the lower end of the guard is shown bent inwardly at an angle to provide a portion 15 extending in relatively close to the switch mechanism. The box cover when in the closed position preferably comes into proximity to or substantially rests upon the guard plate. By this construction a very compact box is provided and one in which a maximum amount of interior space is provided without unduly increasing the overall dimensions of the box. This inturned portion of the plate prevents insertion of the fingers from below and the front of the guard plate prevents direct access to the live parts of the switch, which in this instance may be the contact terminals 8.

In the first construction disclosed the guard plate is supported, and secured in position by means of supporting brackets 16 mounted on the opposite side walls of the box and extending inwardly into position beneath the guard and a third bracket 17 mounted on the upper or top wall of the box. The guard rests on these three inwardly extending brackets and is shown secured thereto by screws 18, the heads of said screws being shown as seated in depressions 19 formed in the plate. For the purpose of sealing the guard in its protective position, I have shown the side brackets 16 provided with angularly upstanding extensions 20 which project up through slots 21 provided in the guard plate and which are provided at their upper ends with perforations 22 to receive a sealing wire or other suitable sealing means 23. With this construction the guard plate may be readily secured in position over the live switch parts and sealed in this condition. When necessary, however, the guard plate may be entirely removed from the box by breaking the seal and taking out the securing screws 18.

In the modification illustrated in Fig. 4 the guard is made a permanent part of the switch box by permanently hinging it there.

to at one end. This hinge is provided by a strap 24 secured to the back of the guard plate substantially at the end thereof, which strap is provided with angularly turned hinge lugs 25 pivoted to the opposite side walls of the box at 26. With this construction the guard may be readily swung up out of the way to expose the live parts of the switch and when in use can be secured in place by the sealing means already described.

I claim:

1. An enclosed switch construction comprising a box having a cover, stationary and movable switch members mounted therein, detachable fuses connected with said switch members, stationary supports in said box, a guard plate detachably secured to said supports in said box and comprising a main portion extending over said stationary and movable switch members and an angularly disposed portion extending inwardly from the main portion toward said fuses, said construction permitting free access to said fuses when the cover of the box is open and without movement of said guard plate but said guard plate preventing access to said stationary and movable switch members when the box is open.

2. In an enclosed switch construction a box including a cover, a switch mounted therein and including stationary and movable members, external means for operating said switch independently of the position of the cover, fuses connected to said switch members, and a guard plate detachably secured in said box and covering and preventing access to said stationary and movable switch members when the cover is open and having an extension projecting over parts of said fuses but permitting access to said fuses when said cover is open.

3. In an enclosed switch a box including a cover, a switch mounted in said box and having stationary and movable switch members, fuses connected with said switch, brackets secured to the end and sides of said box, a guard plate detachably mounted on said brackets covering said switch members and

having an extension projecting toward said fuses but permitting access to said fuses when said cover is open.

4. As an article of manufacture a sheet metal guard plate for an enclosed switch comprising a substantially flat main body portion adapted to be detachably secured in the body of a switch box to cover the stationary and movable members of the switch mounted therein and having an angularly disposed extension projecting from the plane thereof and adapted to prevent accidental contact with the switch members but to permit access to the said switch fuses when the cover of the box is open.

5. In an electric switch, a switch box, inwardly extending supporting brackets on different side walls of said switch box, a guard plate supported by said brackets and having a depressed seat, one of said brackets having an upstanding lug and the guard plate having an opening therein through which said lug is passed.

6. In an electric switch, a switch box, inwardly extending supporting brackets on different side walls of said switch box, a guard plate having depressed seats supported by said brackets, some of said brackets having upstanding lugs, the guard plate having openings therein through which said lugs are passed and sealing means engaged with said upstanding portions of the brackets above the guard plate.

7. An enclosed switch construction comprising a box including a cover, brackets secured to the inner side walls of said box, stationary and movable switch members mounted in said box, fuses connected to said switch members and a guard plate detachably secured to said brackets and extending over said switch members and having an extension projecting toward said fuses to prevent accidental contact with said switch members when the cover of the box is open, but to permit free access to said fuses without disturbing said guard plate.

FRANK T. WHEELER.
